MAIL CRANE

Irvin Pendleton, Campbellsburg, Ky.

Application June 2, 1945, Serial No. 597,311

3 Claims. (Cl. 258—1.2)

1

This invention relates to mail bags of the type designed for use in connection with cranes holding said bag for delivery to a passing train or vehicle and it has for its principal object to improve the safety of operation of the arrangement by means of which the bag is caught or picked up, to make the arrangement fit for operation in connection with vehicles travelling at high speed such as fast trains, or airplanes and to provide a construction of this type which will not materially change or complicate the approved type of structure.

Two kinds of structures have been in practical use for the purpose above specified. The older type of mail bag was fastened to a ring or to a chain which was suspended or stretched on pins or hooks of a station device. A crane arm or carrier on the train provided with a hook caught the ring or chain and carried it along together with the mail bag attached thereto.

The operation of such a device is, however, only tolerably safe at slow speed. It has the great advantage that once the ring or chain was caught it was safely held but it had, among others, the disadvantage that the mail bag and support were not protected against free swinging movement.

As such a movement causes a very marked unsafety of operation, may cause damage and is even dangerous, especially where heavy mail bags are used, a second method has been employed, according to which the mail bag is carried on both ends between horizontal arms of a station device which are under resilient pressure. These arms carry pins or spring hooks engaging hooks or rings on the mail bag and thus hold the latter fully stretched out and in an upright position between them. Usually a cord running from one end of the mail bag to the other provides a means for catching the mail bag, which as a rule is a double bag with a constricted middle portion. Either the latter is caught by a forked crane arm on the train or the said arm catches the mail bag between its constricted middle portion and the cord stretched between the two larger end portions.

The present invention is an improvement of the last named method according to which the mail bag is held in an upright position at the end of stationary crane arms which are under spring pressure. It consists in an additional spring pressed device attached to the stationary carrier which is able to hold under spring pressure a cord, strap, wire or other device attached to the mail bag and it, therefore, is capable of

2

holding such cord, straps, bands, or wire in a distended condition so that together with the mail bag itself and with any suspension or extension cord fixed to the mail bag it may form a loop covering a wide area. The spring pressure takes up any slackening of the cord, strap or wire and therefore prevents swinging of the same.

The device presents a much wider area to the crane arm on the train than heretofore attainable. Thereby the number of failures to catch the mail bag is reduced to a minimum even if trains are travelling with high velocity. It will also be noted that the device may operate from both sides alike.

15 The new device moreover extends the area of the loop by attaching the latter not directly to the stationary crane arm but by means of extensions in the form of cords, straps, wires, bands or the like attached to its ends. These

20 extensions are caught and held by the stationary arms and thus determine the width of the loop at the end. The loop may thus cover a triangle of any size, with all corners held firmly and resiliently on the stationary device.

25 The triangular loop is much more easily caught by a crane arm on a vehicle than the small loops formed by cords attached to both ends of the mail bag and it may even be arranged in such a way that the triangular loop is very large and

30 may be caught by an airplane by means of a cable lowered from said plane and provided with a catching hook.

Two modifications of the invention are illustrated and described but it is to be understood that these modifications show the invention merely by way of example and that further embodiments of the invention may be used without departing from the essence of the invention.

In the accompanying drawings:

40 Figure 1 is an elevational view of the arrangement, showing the mail bag suspended in an upright position near a railroad car provided with a device for catching the mail bag.

45 Figure 2 is an elevational side view of the device showing the details.

Figure 3 is an elevational front view of the device.

Figure 4 is an elevational end view of the device when mounted on a mast for the purpose of being caught by a plane.

50 Figure 5 is a partial elevational view of a modification.

Figure 6 is an elevational front view of a mail bag suspended in a horizontal position between carrier arms which are wide apart, so as to pro-

vide a wide basis for the triangular loop. This suspension method is used for airplanes.

The arrangement illustrated in Figure 1 comprises the usual type of mail bag 10 having a constricted middle zone which is provided with hooks, rings or eyes 11 at its ends. These eyes are held on bolts 12 which are pivotally mounted on crane arms 13, 14, hinged to an upright 15, by means of hinges 16. The upper arm 13 is preferably under the tension of a spring 17 which will move it upwardly, while the lower arm 14 simply falls down by gravity if not held.

Both arms are held in a horizontal position by the mail bag 10 when the eyes 11 are inserted over the pivoted ends of the bolts 12.

The upright 15 carries a support 20 in which the loop catching piece 21 is guided. This piston-like piece passes through a guide hole 22 and is provided at one end with a head 23, carrying an upright bolt 24. On the other end it carries a disk 25 against which a spring 26 is pressing which finds its support on a washer 36 pressing against the support 20.

The loop forming cord on strap 27 is attached to the upper and lower part of the mail bag in the modification shown in Figure 2 either directly or by means of snap fasteners 45 which permit to attach it to back on clamps 46 attached to the mail bag. This cord or strap carries a ring or eye piece 28 which may be slid over the upright bolt 24 on head 23. The spring 26 retracting the piston-like piece 21 then holds the cord 27 in such a tensioned position under spring pressure that an approximately triangular loop is formed by the mail bag and the two sections of the cord 27 which are held by the eye piece 28.

A railroad car 29 provided with a crane arm 30 will bring the forward end 35 of its arm into the triangular area enclosed by the loop 27 and will seize the mail bag with a great degree of safety, as the area of the loop is much greater than that covered by the lateral movements of the crane arm, even under the most unfavorable conditions when the car is jerking heavily. All the parts of the mail bag or connected with the mail bag are moreover firmly held against swinging or similar movements.

The mail bag may be easily detached from the crane arm, even if the latter is at a distance from the car window by opening the strap fasteners.

To enlarge the area of the loop the mail bag may be attached to extension straps or bands 32 with its ends, which are provided with the suspension eyes or rings. The cord 27 is then attached to the extension straps, strips or bands and the area of the loop, as is clearly seen from Figures 5 and 6, may be extended considerably.

For catching mail bags from an airplane by means of a cable 33, as indicated in Figure 4 it is preferable to suspend the mail bag horizontally on a mast 35 or on a plurality of masts, the latter carrying the structure 37, for suspending the mail bag in a horizontal position. The arms 38 need not be hinged or pivoted in this case, as the airplane can catch the bag merely by means of a hook 39 and will lift it above the structure.

The sections 39 of the cord forming the loop which are attached to the extension sections 32, 38 are fixed on a hook or eye 41 which is held

by a bolt 42, stretching the loop and holding it taut against swinging.

The operation of the device will be self-evident from the above description.

5 It will be obvious to persons skilled in the art that the specific details of the construction may be changed or varied to suit special purposes.

I claim:

- 10 1. A mail bag suspension arrangement for mail bags to be picked up by vehicles in motion, comprising a crane with a fixed member and movable mail bag suspension arms, adapted to be moved away from each other, projecting studs on said arms extending into the direction along which the mail bag is moved during the pick-up operation for slidably holding the mail bag, means attached to the ends of the mail bag for engaging said studs adapted to slide along said studs, a cord attached to the said end portions of the mail bag, to form a loop with the body of the mail bag, means attached to said cord for detachably holding it, a spring pressed slideable member mounted on the fixed member of the crane provided with a stud, for engaging the cord holding means and for drawing the cord and the mail bag inwardly towards the crane, thus simultaneously extending the loop to maximum length and holding the mail bag on the studs of the movable crane arms.
- 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750
2. A mail bag suspension arrangement for mail bags to be picked up by vehicles in motion, comprising a crane with a fixed member and with movable mail bag suspension arms adapted to be moved away from each other, projecting studs on said arms for slidably holding the mail bag, extension cords attached to the center of the end portions of the mail bag for extension along the longitudinal axis of the mail bag, means attached to the ends of the extension cords of the mail bag for engaging said studs, said means being adapted to slide along the same, a cord attached to said extension cords for forming a loop with the body of the mail bag, means attached to said cord for detachably holding it, a spring pressed slideable member mounted on the fixed member of the crane provided with a stud, for engaging the cord holding means and for drawing the cord and the mail bag inwardly towards the crane, thus simultaneously extending the loop to maximum length and holding the mail bag on the studs on the movable crane arms.
3. A mail bag arrangement as specified in claim 2, with a mail bag provided with extension cords extended horizontally and with a spring pressed member arranged vertically for forming a loop to be caught by airplanes.
